UNITED STATES PATENT OFFICE.

ERNST H. HUENEFELD, OF CINCINNATI, OHIO.

OVEN-DOOR.

943,546.

Specification of Letters Patent. Patented Dec. 14, 1909.

Application filed April 16, 1909. Serial No. 490,349.

To all whom it may concern:

Be it known that I, ERNST H. HUENEFELD, of Cincinnati, in the county of Hamilton and State of Ohio, have invented certain new and useful Improvements in Oven-Doors; and I do hereby declare the following to be a full, clear, and exact description of the invention, such as will enable others skilled in the art to which it appertains to make and use the same.

This invention relates to improvements in domestic ovens and more particularly to an improved door therefor,—the same being applicable for the ovens of cooking ranges, 15 gas-stoves and portable ovens.

The object of my present invention is to provide an oven door having a transparent panel therein, which latter shall be so supported and connected with the door frame 20 as not to be liable to breakage on account of unequal expansion and contraction of the main frame of the door and the transparent panel.

A further object is to so support a glass panel in an oven door without the use of asbestos or similar packing and yet prevent breakage of the glass on account of changing degrees of heat to which it may be subjected.

With these objects in view the invention consists in certain novel features of construction and combinations of parts as herein-after set forth and pointed out in the claims.

In the accompanying drawings, Figure 1 is a front elevation of a door embodying my improvements. Fig. 2 is a rear view with the rear plate removed. Fig. 3 is a transverse sectional view. Fig. 4 is a detail view of one of the holding strips for the glass panel, and Fig. 5 is a modification.

1 represents the main frame of the door and consists of a casting provided at its lower corners with pintles 2 by means of which the door can be hinged to the front plate of an oven. In order that this frame shall present a pleasing appearance its outer surface may be convexed between the corner portions and preferably coated or plated with some bright metal or otherwise 45 polished. The upper member of the frame 1 is made intermediate of its length with an enlarged portion 3 which forms a seat for a bracket 4 and this bracket carries a suitable latch 5 and a handle 6 to operate said latch 50 and to manipulate the door.

The rear face of the frame 1 is provided

near the corners and also at intermediate points with bosses 7 having threaded sockets 8 for the reception of screws, and said bosses may be connected by strengthening ribs 9. 60 The inner edges of the frame 1 constitute, on the rear face of said frame, ledges or seats 10 for a sheet metal frame 11. The external dimensions of this frame 11 are appreciably greater than the internal dimensions of the frame 1, but the internal dimensions of the frame 11 are considerably less than the internal dimensions of the frame 1 so that when the frame 11 is in position against the back of the frame 1, a considerable portion of said frame 11 will appear within the frame 1 when the latter is viewed from the front. The bosses 7 intermediate of the corners of the frame 1 will serve to prevent displacement of the frame 11. The 75 frame 11 is provided at its outer edges with flanges 12 and at the inner edges of said frame, a seat is provided for a glass panel 13. Between the edges of the glass panel 13 and the flanges 12 at the outer edges of the frame 11, spacing strips 14 (preferably of sheet metal) are disposed and each of these spacing strips is provided at both of its longitudinal edges with flanges 15 which are of such depth that when the strips are 80 placed in position, the upper edges of said flanges will be substantially flush with the upper edges of the flanges 12 and the upper or rear face of the glass panel.

A sheet metal rear frame 16 is placed on 90 the bosses 7 of the frame 1 and covers the frame 11, the spacing strips and the edges of the glass panel. The rear frame plate 16 is secured in place by means of screws 17 which pass through suitable holes in said 95 plates and enter the threaded sockets 8 in the bosses 7. With this construction, it will be observed that the glass panel is supported and held in position between two sheet metal frames and that said glass panel makes no contact with the casting which 100 composes the main frame 1. It has been demonstrated that with such construction, all danger of breakage of the glass panel on account of unequal expansion and contraction of the holding frame and the glass, will be avoided, and it is believed that this is largely due to the fact that the expansion and contraction of the sheet metal frames 105 will be practically equal to that of the glass panel. Two or more rods 18 are secured at their respective ends to the rear 110

frame plate 16 and extend transversely across the glass panel without actual contact with the latter, and serve to support pans which may be withdrawn from the oven 5 when the door is disposed in a horizontal position and protect the glass panel from the weight of such pans and their contents. The rods 18 also serve to prevent accidental breaking of the glass panel should the door 10 be closed against a protruding pan in the oven. The screws 19 which secure the rods 18 in place enter the threaded sockets 8 of intermediate bosses 7 and serve to secure the intermediate portion of the rear frame plate 15 in place.

In the construction shown in Fig. 5, the spacing strips for the glass panel are omitted and a larger glass panel employed,—the flanges at the outer edges of the sheet metal 20 frame 11 serving, in this case, to prevent displacement of the glass panel.

Having fully described my invention what I claim as new and desire to secure by Letters-Patent, is,—

25 1. In an oven door, the combination with a cast metal main frame provided with a series of lugs and having seats, of two sheet metal frames secured to the rear side of the main frame, one of said sheet metal frames 30 being located between said lugs and against said seats of the main frame, and a transparent panel having its edges confined between said sheet metal frames and without contact with the cast metal frame, said sheet 35 metal frames constituting the sole attaching means of the transparent panel to the cast metal main frame and separating the transparent panel from contact with the said main frame.

40 2. In an oven door, the combination with a main frame, of a sheet metal frame seated against the rear face of the main frame and provided at its edges with flanges, a transparent panel seated against the rear face of

the sheet metal frame, spacing strips disposed between the edges of the transparent panel and the flanges of said sheet metal frame, and a rear frame plate covering the edges of the transparent panel, the spacing strips and the sheet metal frame and secured 50 to said main frame.

3. In an oven door, the combination with a main frame, of a sheet metal frame seated against the rear face thereof and provided at its outer edges with flanges, a transparent panel seated against said sheet metal frame, sheet metal strips disposed between the flanges of the sheet metal frame and the edges of the transparent panel, each of said strips being provided at its longitudinal edges with flanges, and a rear sheet metal frame plate covering the edges of the glass panel, the spacing strips and the sheet metal frame, and fastening devices securing said rear frame plate to the main frame.

4. In an oven door, the combination with a cast metal main frame provided on its rear face with bosses, of a sheet metal frame seated against the main frame and held against displacement by said bosses, a glass panel seated against said sheet metal frame, means around the edges of the glass panel for holding said glass panel against displacement, a rear frame plate covering the edges of the glass panel and the sheet metal frame, rods extending across the opening of said frame plate and the glass panel in said opening, and fastening devices securing said frame plate and said rods to bosses of the main frame.

In testimony whereof, I have signed this specification in the presence of two subscribing witnesses.

ERNST H. HUENE Feld.
